UNITED STATES PATENT OFFICE.

CHARLES WEBER, OF NEWARK, NEW JERSEY.

POWDER-BOX.

1,331,547.

Specification of Letters Patent. Patented Feb. 24, 1920.

Application filed May 10, 1919. Serial No. 296,164.

To all whom it may concern:

Be it known that I, CHARLES WEBER, a citizen of the United States, and resident of Newark, in the county of Essex and State 5 of New Jersey, have invented certain new and useful Improvements in Powder-Boxes, of which the following is a specification.

The object of my invention is to provide a box or container for dispensing powder, 10 with a closure for the outlet perforations of the box adapted when rocked to cause agitation of the box, whereby the powder will be discharged from the box as desired.

In carrying out my invention I provide 15 a box having a head or neck portion provided with apertures and a closure or cover rotative over the same adapted to close or open said apertures, said closure having a projection adapted to coöperate with corrugations on said head or neck, whereby to cause agitation of the box, by means of which agitation the powder will be ejected through the apertures.

My invention also comprises novel details 20 of improvement that will be more fully hereinafter set forth and then pointed out in the claims.

Reference is to be had to the accompanying drawings forming a part hereof wherein 25 Figure 1 is a partly broken side view, on an enlarged scale, of a powder box embodying my improvements;

Figs. 2 and 3 are cross sections, substantially on the line 2—2 in Fig. 1, showing the 30 closure in different positions; and

Fig. 4 is a section on the line 4,4 in Fig. 1.

The box 1 may be of any suitable shape and dimensions and the same is shown provided with a top 2, which parts may be as 35 usual, such as for so-called talcum powder boxes. The top 2 is provided with a head or outlet portion 3 the outer part of which is shown in spherical form whereby a correspondingly shaped segmental-like closure or 40 cover 4 is adapted to sweep over the outer spherical surface of head 3 close thereto. Head 3 at one part is provided with one or more perforations 5 for discharge of the powder, which perforations are adapted to 45 be closed by the closure or cover 4 (Fig. 2) and to be opened when said closure is swung to the left as in Fig. 3. The closure or cover 50 4 is shown provided with a finger piece 6 projecting outwardly from one edge portion, and the closure is also provided with a projection 7. Said finger piece and pro-

jection may be stamped from the material of closure 4 by suitably slitting the material and bending said parts as required. The head 3, on the side opposite the perforations 5, is shown provided with transverse corrugations 8 disposed in consecutive order along the periphery of head 3 in the direction and path of travel of projection 7. Said projection 7 is preferably bent outwardly 65 slightly from the arc of the surface of head 3 and provided with an offset portion 7^a, which may be made by denting the metal of said projections. When closure 4 is swung from the position shown in Fig. 2 toward 70 the position shown in Fig. 3, and reversely, offset 7^a of projection 7 will slide from one corrugation to another in a snapping-like manner, so that when the box is held in the hand and the closure 4 is rocked back 75 and forth the sliding of projection 7 along the corrugations 8 will cause the box to be agitated. By preference closure 4 is normally held closed by a spring. I have shown closure 4 pivotally attached to head 80 3 by means of a shaft or rod 9 journaled in holes in said head and extending across the same. A coiled spring 10 upon said rod coöperates with top 2 to retain the closure over aperture 5. One part of 85 closure 4 is secured to rod or shaft 9, as at 12 and said spring is shown coiled upon opposite end portions of rod or shaft 9, an intermediate portion 10^a of said spring bearing against a lateral portion 9^a of rod or 90 shaft 9 and the extended ends of said spring bearing against top 2, whereby said spring will tend to cause the closure or cover normally to close the perforations 5 in the position shown in Figs. 1 and 2. When the closure 95 is rocked reversely and released the tension of the spring will serve to restore the cover to the position shown in Fig. 2. A scraper operated with closure 4 is adapted to travel within head 3, for which purpose I have 100 shown the lateral portion 9^a of rod or shaft 9 curved at 9^b to bear against the inner surface of head or neck 3 and to swing back and forth with closure 4 along perforations 5 to 105 scrape powder therefrom to keep the perforations from becoming clogged.

In using my improvement the box may be held in one hand and tilted with the perforations 5 downwardly, and a finger of the hand may be used upon the finger piece 6 110 to rock closure 4 back and forth so that the projection 7 will correspondingly slide along

and over the corrugations and by contact therewith will cause the box to be agitated, and thereby the contents thereof will be discharged to the desired extent, and while the 5 contents thus are being discharged they may be directed as desired upon the hand or other object without discharging an undue amount. With ordinary forms of powder boxes known to me having perforations in the top 10 it is customary to forcibly manipulate the box to eject the powder, which will have a tendency to discharge more than may be required or not directly upon the object desired, with consequent loss of powder, 15 whereas with my improvement the perforations 5 may be held directly over the object while the closure is being rocked, and when the closure is released the spring will cause it to be automatically closed over the aper- 20 tures and there remain until again used. My improvements are useful for discharging talcum powder, soap powder, salt, sugar, pepper and other powdered materials.

My improvements are not limited to the 25 particular details of construction disclosed as they may be varied, within the scope of the appended claims, without departing from the spirit of my invention.

Having thus described my invention, what 30 I claim and desire to secure by Letters Patent is:—

1. A powder box provided with a perforate portion, a closure for the said perforations movably supported by the box, and 35 means coöperative between the closure and the box to cause agitation of the latter when the closure is operated and exposes the perforation.

2. A powder box provided with a perforate portion, a closure movably carried by the box and adapted to pass over the perforations, one of said parts having a projection and the other of said parts having corrugations coöperative with said projection for 40 causing agitation of the box when the projection and corrugations are moved relatively one to another while the cover exposes the perforate portion.

3. A powder box having a head portion 45 provided with one or more perforations, a closure pivotally carried by the box and adapted to open and close the perforation or perforations, said closure having a projection and said head portion having corruga- 50 tions on the side opposite the perforation or

perforations coöperative with said projection whereby the box will be agitated when the projection passes in contact with the corrugations while the closure opens the perforation or perforations. 60

4. A powder box having a head portion provided with one or more perforations, a closure pivotally carried by the box and adapted to open and close the perforation or perforations, said closure having a projec- 65 tion and said head portion having corruga- tions on the side opposite the perforation or perforations coöperative with said projection whereby the box will be agitated when the projection passes in contact with the 70 corrugations, and a spring coöperative with said closure to normally retain the same in perforation closing position with the projection away from the corrugations.

5. A powder box provided with a head 75 having a portion in spherical form, and a closure having a corresponding spherical shape to travel over said head and provided with a projection, said head being provided with one or more perforations to be closed 80 by the closure, said head on the side opposite the perforation being provided with a series of transversely disposed corrugations extending along the line of travel of said projection adapted to coöperate therewith 85 to cause agitation of the box when said projection passes in contact with the corrugations.

6. A powder box provided with a head having a portion in spherical form, and a 90 closure having a corresponding spherical shape to travel over said head and provided with a projection, said head being provided with one or more perforations to be closed 95 by the closure, said head on the side opposite the perforation being provided with a series of transversely disposed corrugations ex- 100 tending along the line of travel of said projection adapted to coöperate therewith to cause agitation of the box when said projection passes in contact with the corrugations and a spring coöperative with said box and closure to normally retain the closure over the perforation with the projection away from the corrugations. 105

Signed at New York in the county of New York and State of New York this 9th day of May A. D. 1919.

CHARLES WEBER.
